WALTER RING, OF GOSPORT, INDIANA.

Letters Patent No. 70,266, dated October 29, 1867.

IMPROVEMENT IN TRAM-STAFF FOR GRINDING-MILLS.

The Schedule referred to in these Letters Patent and making part of the same.

TO ALL WHOM IT MAY CONCERN:

Be it known that I, WALTER RING, of Gosport, in the county of Owen, and State of Indiana, have invented a new and improved Pivot Gauge-Staff and Tram for Millstones; and I do hereby declare that the following is a full, clear, and exact description thereof, which will enable others skilled in the art to make and use the same, reference being had to the accompanying drawings, forming part of this specification, in which—

Figure 1 is a side elevation of a millstone with the gauge-staff and tram applied to it.

Figure 2 is a plan of the same.

Figure 3 is a vertical section taken in the line *x x*, figs. 1 and 2.

Figure 4 is a top view of the millstone with the tram removed.

Figure 5 is a plan of an internal part, or a bush in the tram.

Figure 6 is the same with other connected parts.

Similar letters of reference indicate like parts.

This invention relates to a device for gauging and staffing or levelling millstones accurately, and plumbing the spindle truly, by which this important part of a miller's work may be performed readily and perfectly by any one, even the most unskillful, with absolute certainty. This device is an adjustable pivot-gauge staff and tram by which the spindle may be easily set perfectly true, and the burr-stone taken out of wind and made level ready for dressing.

A represents either an upper or lower millstone, provided with a bail, *a*, and a proof or temporary spindle, *b*, by which an upper stone or runner is gauged and trammed, as seen in figs. 3 and 4. The proof-spindle *b* is secured in place temporarily by the driver or spider-frame *c*, fitted in and fastened to the face of the stone by screws *d d*, which pass down through the eye of the stone to the bottom, when they screw into a barrel-plate, *e*, let into the stone. The stone being thus prepared for trammimg, is turned up level, and the gauge-staff or tram applied, as shown in fig. 1. The tram consists of an iron plate or staff, equal in length to the diameter of the stone, and planed perfectly true on the face, to be used as a proof-staff, as subsequently explained. *B B* is the iron proof-staff, to the face of which is fitted and fastened by screw-bolts *ffff* a wooden staff, *C C*, also made perfectly true on the face, next the stone. On the top of the iron staff *B B* is bolted a central iron arch, *D*, by screws *g g*. In the crown of the arch is a sleeve-box, *h*, in the lower part of which is fitted a sliding pivot-pin, *i*, projecting underneath, which centres on the upper end or point of the spindle *b*. In the upper part of the box is also fitted a thumb-screw, *j*, for raising or lowering the pivot-pin *i* to adjust the spindle. The iron staff *B B* is provided with spirit-levels *k k*, one at each end. The middle of the iron staff *B* is made circular, with a hole in it to go over and around the spindle, and on the lower side a bush-plate, *m*, is screwed to it, as shown in place in fig. 3, and detached in figs. 5 and 6. The bush-plate *m* is surrounded by a collar, *m¹*, in opposite sides of which are projecting set-screws *m² m³*, fig. 6, for moving it around the bush to centre and plumb the spindle, and securing it fast to the bush-plate *m*, when required, as subsequently explained. The collar *m¹* rises a little above the face of the bush-plate *m*, and is provided on the inside with four spurs or lugs *n n n n*, set diametrically opposite each other, and which ride over the edge of the bush-plate, for the purpose of moving and bearing against the eccentric sides of four centro chucks or followers *n¹ n¹ n¹ n¹*, which are pivoted by screws *s* upon the face of the bush-plate *m*. When the gauge-staff *B B* is placed upon the spindle to centre and plumb it, by moving the collar around the bush-plate *m*, the lugs *n* bear against the eccentric followers *n¹*, and push them inward till they touch the spindle *b*. The staff *B* is then made fast to the spindle, so that the wooden part *C* shall clear the face of the millstone at its highest points, by means of the set-screws *m²*, while at the same time the pivot-pin *i* is set upon the point of the spindle *b*, and fixed in place by the thumb-screw *j*. The followers *n¹* are covered with a plate, *n²*, seen in fig. 3, to protect them. It will be seen that when the pivoted gauge-staff has been centred upon the spindle of a bed-stone, as described, the spindle may be made plumb by keying up in the usual way, the spirit-level *k k* being used for this purpose. And in case of a runner the gauge-staff being centred on a temporary or proof-spindle, the stone may be faced perfectly true by turning the staff on the pivot-pin *i*, the high places on the stone being marked by the wooden part, as usual, with the ordinary tram, and cut down until the face is smooth and level.

The work may always be tried by the iron proof-staff *B*, which is placed true on the face, and the wooden

staves C be kept perfectly true, by gauging them from the bottom of the iron proof-staff B, which is a permanent and unchangeable regulator.

Having described the construction and operation of my invention, what I claim as new, and desire to secure by Letters Patent, is—

1. The gauge-staff B, centred upon the millstone by means of the circular centre fitting over and around the spindle b, provided upon its under side with the bush-plate m, having the pivoted eccentric followers n¹, and surrounded by adjustable collar m¹, with lugs n, all constructed and arranged as herein set forth.

2. The combination of the tram and gauge-staff B with the spirit-levels K, substantially as herein shown and described for the purpose specified.

WALTER RING.
